COMPRESSION-OPERATED IGNITION DEVICE.

1,255,242.

Specification of Letters Patent.

Patented Feb. 5, 1918.

Original application filed June 24, 1916, Serial No. 105,649. Divided and this application filed November 15, 1916. Serial No. 181,403.

To all whom it may concern:

Be it known that I, WARREN F. STANTON, a citizen of the United States, residing at Pawtucket, in the county of Pawtucket and 5 State of Rhode Island, have invented certain new and useful Improvements in Compression-Operated Ignition Devices, of which the following is a specification.

My invention is a division of my pending 10 patent application, Serial No. 105,649, filed June 24, 1916, and relates to compression operated ignition devices adapted for use in conjunction with internal combustion engines, pumps, and other devices.

15 The essential objects of my invention are to produce an effective spark for the ignition of combustible gases at a minimum rate of compression, especially at the time of starting so as to render rapid cranking unnecessary; to vary the rate of speed of operation of the device and control the timing of the produced spark under all conditions; to prevent shocks to the armature and oscillating parts of the magneto; to avoid strains to the 20 device caused by the piston reciprocating members, and the explosion of the charge; to avoid noise; to so house the device as to protect the parts from the exterior elements and retain the lubricant; to maintain the parts 25 at a low temperature; to concentrate all wear on easily renewable parts; to utilize portions of the operating mechanism for conducting the generated electrical current; to automatically lubricate the piston; and to 30 prevent sticking of the latter.

My invention consists, therefore, in the means and mechanism for producing the results above specified substantially as herein-after described and claimed, and as shown 35 in the accompanying drawings which form a part of this specification, wherein—

Figures 1 and 2 are plan and side elevations respectively of my ignition device, showing the adjacent part of the engine in 40 section,

Figs. 3 and 4, sections respectively on lines 3—3 and 4—4 of Fig. 2,

Fig. 5, a partial section on line 5—5 of Fig. 3 with a portion of the housing removed,

Fig. 6, a bottom plan view of the armature returning mechanism,

Fig. 7, a rear end elevation of the ignition device,

Fig. 8, a detail fragmentary plan of one 55 end of the armature returning mechanism,

Fig. 9, a section on line 9—9 of Fig. 3,

Fig. 10, a section on line 10—10 of Fig. 2, and

Figs. 11, 12, 13 and 14, sections of modified 60 forms of cushioning devices.

Like reference characters indicate like parts throughout the views.

The device is shown in the present instance mounted in the wall 13 of the cylinder of 65 an internal combustion engine wherein 15 is the compression area or combustion chamber. An opening 16 in the cylinder wall accommodates the rear portion of the igniter plug or make-and-break igniter 17, which is 70 attached to the engine in the present instance by an intermediate annular flange 18 carrying bolts 19 engaging in threaded cavities 20 in the cylinder wall.

Mounted upon the plug in any convenient 75 manner is a magneto or generator. In the present instance a bracket arm 22 has on one end an attaching plate 23 fixed by screws 24 to the flange 18, and is integral at its other with the frame or casing 26 of the magneto 80 which has a hollow-cylindrical upper portion 27, provided with an opening 28 in its top which is closed by a removable cap or cover 29 retained in position by a resilient finger 30 pivoted on a screw 31 in the casing. 85 The casing portion 27 has integral extensions 33 and 34 in alignment with each other. The former has a longitudinal bore 35 in line with a piston chamber 36 extending through the plug. The extension 33 has 90 transverse grooves 37 at its end adjacent the plug to form an air passage communicating with a piston chamber 36. An asbestos pad 38 separates the flange 23 from the flange 18, and there is a piston 40 whose end face 95 is exposed to the explosion chamber 15 of the engine. This piston comprises a wall 42 and has upon its exterior spaced annular grooves 43. The piston rod comprises preferably a section 45 rigid with the piston, 100 and a section 46 loosely connected to the rigid section. This connection in the present instance comprises a cylindrical head 48 on section 45 loosely retained in a cavity 49 in the end of section 46 by a flange 50. A 105 hardened convexity or button 51 at the end of the cavity forms a bearing for the head. A T-slot 54 in the side of section 46 permits

the insertion of the head 48. The piston sections are relatively rotatable and have capacity for assuming angular relations with each other. The section 46 extends through 5 passage 35 in the extension 33, also across the casing portion 27, and into the extension 34.

The extension 33 has also a passage 58 in alignment with a cylindrical bearing 59 in 10 the extension 34 parallel with a passage 60 in the latter and with the passage 35. There is a bore 62 passing longitudinally through the plug in alignment with the passage 58. In the bore 62, passage 58 and seat 59 is an 15 axially movable grounded electrode 64 fixed to whose inner end is a contact finger 65 within the compression chamber. A second electrode 67 is fixed in the plug longitudinally thereof and is separated therefrom by 20 an insulating sleeve 69. This electrode extends into the combustion chamber and has a lateral projection 70 in the path of the vibratory finger 65. This electrode terminates in a binding post 71.

25 The outer end of the piston rod is journaled or slidable in a removable bearing 72 in the passage 60 of the extension 34. It has an annular shoulder 73 abutting against a shoulder 74 in said extension, and the rear 30 face of said shoulder has abutting thereon the end of a thimble 76 having a thread 77 engaging a thread 78 in the extension. In the thimble is a slidable cap 79 of sufficient diameter to receive the section 46 as a sliding fit, and whose open end abuts against the bearing. In its closed end is a pad 80 of leather or similar material, against the cap abuts one end of a helical spring 81, whose other end rests against the closed end 40 of the thimble. A removable bearing 82 surrounds the section 46 in the extension 33 and has a shoulder 83 abutting against a shoulder 84 in said section. The piston section 46 has two annular flanges 85 and 86, 45 and against the flange 85 abuts one end of a compression spring 87, whose other end abuts against the shoulder 83.

The reciprocation of the piston vibrates the electrode 64 thus. Upon the latter member is fixed by a clamping screw 89, or otherwise, a collar 90 carrying a finger 91 provided with a cam face 92 as shown in Fig. 9, which is in the path of one of the flanges 86, and is normally maintained in the path 55 by a torsional spring 93 surrounding the electrode and fixed at one end to the screw 89 and at its other end in a cavity 94 in the casing.

60 The magneto or generator, as herein shown, is of the ordinary type comprising the casing 26 carrying magnets 95 and the armature shaft 96 journaled in an upper and lower bearing 97 and 98. Fast to the upper end of the armature shaft is a flat lever or 65 crank 101 having near its end a crank pin

102 which extends between the flanges 85 and 86.

The bearing 98 is in an extension 99 of the casing 26, and the latter has an annular channel 103 to receive the hub 104 of an arm 70 105 oscillatory on the extension.

In the present instance the channel is bounded by a shoulder 108 on the casing exterior, and by a flange 107 on the lower end of the bearing member 98. Attached to the 75 lower extremity of the armature shaft 96, by a set screw 109 or otherwise, is a crank arm 110. Passing through an opening 112 in the arm is a crank pin 114 having the end 115 of the conductor 149 wound around it, 80 and provided with a head 116 on its rear end, and a nut 117 against which abuts a disk 118 loose on the pin and provided with a peripheral groove 119, said disk being retained by a cotter pin 120. Seated in the 85 groove is the hooked end 121 of a retractile spring 122, whose opposite end 123 is fixed in an ear 127 on a plate 128 slidable on the lower face of the arm 105 and provided with a longitudinal slot 129 traversed by a screw 90 130 having a head 131 which loosely abuts against the plate and has a diametrical hole 132 to slidably receive a pin 133 journaled in a lug 135 on the arm 105, and provided with a thread 137 engaging in a threaded 95 opening 139 in the ear 127. A milled head 141 upon the end of the pin has an adjacent shoulder 142 adjacent the lug 135. Upon the extension 98 is a lug 143 provided with a curved surface which is preferably a cam 100 face 144, having a series of cavities 145 adapted to form seats for the end of the pin 133 and lock the arm 105 by virtue of spring 122, in the radial position assumed by the latter. The longitudinally slidable capacity 105 of this pin permits it to be withdrawn for insertion into any cavity or outside of the segment. By rotating this pin the tension on the spring 122 may be varied because of the threaded connection of the plate 128 110 and the threaded portion 137 of the pin.

The armature winding 146 has one terminal 147 grounded in the armature shaft, and its other terminal 149 passes through an opening 150 into the hollow lower portion 115 of the shaft, thence to the crank pin 114, through current conducting disk 118, through the spring 122 to a connecting plate 152 upon the spring and attached to a conductor 153 which extends to the binding post 71 of the fixed electrode. The described terminal and current conducting members are protected by insulating sleeves 155 and 156 in the armature shaft and crank disk respectively, as well as by an insulating 125 block 157 in the lug 127. While the described electrical circuit is preferred it will be understood that it is not imperative.

It is desired to automatically lubricate the piston in proportion to the number of 130

operating strokes of the piston. To this end means actuated by the piston is provided as follows. Recess 158 in the flange 18 has an opening into the piston chamber 36, leading into which is a vent hole 159. Resting on the flange is the shank 160 of an oil cup 161. Within the opening 158 is a plug 162 having a threaded connection with the flange and of reduced diameter at 10 its lower portion to allow air communication between the cylinder chamber and the vent hole 159. A head 166 upon the plug abuts upon the base of the oil cup and has horizontal openings 168 leading to a vertical opening 169 extending longitudinally through the shank or plug 162. Loose in the latter opening is the stem 170 of a valve 171 having a seat 172 in the head at the intersections of the openings 168 and 169. A 15 cylindrical recess 174 is located in the head above the valve in which is seated a helical spring 175 downwardly pressing upon the valve, and normally maintaining the projecting lower portion of the valve stem in 20 the path of the piston wall 42, whose advance elevates the valve and permits the flow of the lubricant from the oil cup through the passage 169 to the grooves in the piston flange. Any heated gases which 25 escape from the engine chamber around the piston escape through the vent opening 159. This vent is independent of the cooling openings 37 which together with the asbestos layer 38 serve to maintain the parts supported by the plug at a relatively low temperature.

For the protection of the parts below the arm 105 there is provided, as shown in Fig. 2, a removable housing cap 176 whose upper edge abuts against the margin of the arm, and is provided at one end with a vertical slot 177 to admit therethrough the head 141 of the pin 133. This cap is retained in position by one or more spring 40 fingers 179 riveted to its side, or opposite sides, as at 180, and engaging the edge of the arm.

The operation of the mechanism is as follows. The piston is forwardly impelled by the compression of the charge in the engine, turning the armature a part of a revolution through the members 45 and 46 and the crank member 101, thereby generating a sparking current in the electric circuit. The advance of the member 46 causes the flange 86 to contact with the cam 91 on the electrode 64 thus forcing the contact arm 65 away from the electrode 67 to create a spark. The spring 93 returns the arm to 50 its original position. The advance of the member 46 is cushioned by the buffer spring 81 and by the pad 80 whereby noise and shock to the structure is prevented. The spring 87 cushions the movement of the member 46 55 in its opposite travel. The armature and

piston are returned to their initial positions by the retractile spring 122 operating through the crank arm 110. A change in the speed of piston return is attained by varying the tension of the spring 122 by 70 turning the pin 133.

It is desirable to produce a spark at the lowest rate of compression, as when cranking, and at extremely low speeds of the motor, because the compression in the cylinder must be built up near to highest compression before the ignition devices operates. It is, therefore, necessary that when the required pressure is reached the force restraining the piston suddenly releases the mechanism in order that the pressure may impart sufficient velocity to the armature to generate a current to furnish a spark. 75

It is essential that the initial restraining torque exerted by the spring 122 upon the 80 armature shaft be greater at the moment of starting of the device than at any later perior of its advance.

After the engine is running, on the other hand, the restraining action of the spring 90 may be varied from a high initial resistance relative to the subsequent resistance, to a ratio of a lower initial resistance relative to the subsequent resistance. This is accomplished by changing the axial position 95 of the arm, and the values of any of these ratios may be varied within certain limits by increasing or decreasing the spring tension by turning the threaded pin 133 and by swinging the arm 105 to any of its 100 radial positions. The member 133 changes the magnitude of the ratio, but not sufficiently to reverse the ratio. The movement of the arm, however, is sufficient, without turning the member 133, to reverse the ratio. 105

The arm is turned to the position shown in broken lines in Fig. 6 when the compression is being slowly built up at the time of starting, or at low speed. As the speed increases the arm is swung in the direction of the arrow a greater or less distance. Thus the timing of the spark is controlled under all conditions, and the rate of speed at which the device operates may be varied. At any desired point of adjustment of the arm the 110 pin 133 enters an adjacent cavity 145 and retains the arm against accidental movement. If, as in this instance, the cavities are disposed on a cam surface the spring tension is further augmented, thus intensifying the spring action already described. If the curvature of the face 144 is arcuate rather than a cam, this auxiliary advantage is lacking. 115

The arm 105 may be immovable when 120 used in connection with motors wherein a wide range of motor speed is absent, but in case of motors having a wide range of motor speed the ratio of the torque exerted by the spring may be varied over a wider range. 130

The operative parts are thoroughly housed against dirt by the cap 176 and by the portion 27 of the casing with its removable cover 29, as well as by the construction of the 5 casing as a whole; and the lubricant is not allowed to escape. The wear occasioned by the member 46 is concentrated upon the bearings 72 and 82 which are easily removable and renewable.

10 It will be observed that the oil cup is located adjacent the engine cylinder where by the utilization of the heat, the oil flows in proportion as required. When the motor is cold little oil is required. As it warms 15 up more oil is required. Furthermore in case of oils of varying densities more thin oil is fed than viscous oil, which is the result desirable for lubrication purposes.

It will be further noted that in the electric 20 circuit certain of the operative parts are employed as conductors, such as the spring 122. This spring because of its accessibility renders it available for repair or substitution.

25 The proximity of the plug 16 to the cylinder chamber has a tendency to heat the piston, as well as the plug excessively, and injury to former is prevented by the hollow character of the piston 40 by virtue of the 30 wall 42. The piston and plug are further cooled by the passages 37 whereby fresh air is induced into the piston chamber and by outlets 159 through which the heated gases escape during the explosion period, thus preventing 35 the mixing of the heated gases with the cooling air within the hollow piston.

The casing adjacent to the plug would become excessively hot by conduction, and to avoid this the heat insulating layer 38 is 40 interposed between the casing and the plug.

The means described for cushioning the thrust of the piston is not exclusive but satisfactory results are attainable by the modified form of structures shown in Figs. 11 45 to 14 inclusive. In Fig. 11 the cushioning means is pneumatic, and in this instance the member 46 has preferably upon its end a head 182, movable in a sleeve 184 which is slidably mounted in the thimble 76. The 50 sleeve has an outer end wall 186 provided with an opening 187, and is provided upon its inner end with an inturned flange 188 adapted to engage the head 182 and to abut against the member 72 at the end of the return 55 reciprocation of the member 46. As the sleeve 184 is shorter than the thimble there exists a resultant air space 189 in the end of the thimble. The head 182 in its advance closes the opening 187 and forces the sleeve outwardly thus compressing the air in chamber 189 and thereby absorbing the shock of the piston advance. The return 60 of the member 46 returns the sleeve 184 to original position by the cooperation of the flange 188 and head 182. This flange may,

however, be omitted and a spring 191 be substituted therefor to effect the sleeve return as shown in Fig. 13 wherein the thimble is provided with an end portion of reduced diameter forming a seat 193 for the end of 70 the spring.

A method of cushioning the piston advance by hydraulic means is shown in Fig. 12 where the thimble 76 has its end portion of reduced diameter to form a chamber 193 75 which is adapted to permit the head 182 to enter.

This chamber and the remainder of the thimble is partially filled with oil 195 or other liquid, and the advance of the piston 80 with the member 46 and head 182 confines the liquid and air in the chamber 193 in a manner to cushion the advance reciprocation of the parts.

The cushioning effect is secured in the construction shown in Fig. 14 by combined spring, pneumatic, and hydraulic means. In this instance the thimble is reduced near its end to form the chamber 193, and is still further reduced at its end to form a seat 90 197 for the end of a spring 198 which extends to the mouth of the chamber 193 and has its confined end fixed to the thimble. The advance of the piston causes the head 182, in its advance, to confine the oil 195, encounter 95 the spring 198, and compress the air in the chambers 193 and 197.

I claim:—

1. In a compression operated ignition device, the combination with an engine cylinder, of an igniter in the cylinder provided with a piston chamber opening into the cylinder, a piston in the chamber exposed to the charge in the cylinder and air passages in the igniter extending from the atmosphere to said piston chamber. 100

2. In a compression operated ignition device, the combination with an engine cylinder, of an igniter in the cylinder provided with a piston chamber extending into the cylinder, a piston in the chamber exposed to the charge in the cylinder, said igniter being provided with air passages extending from the atmosphere to the piston chamber, and with vent openings adjacent the air passages extending to said piston chamber. 110

3. In a compression operated ignition device, the combination with the engine cylinder, of an igniter in the cylinder provided with a piston chamber, and means for introducing atmospheric air into the piston chamber. 120

4. In a compression operated ignition device, the combination with an engine cylinder, of an igniter in the cylinder provided with a piston chamber, and with means for admitting atmospheric air to the chamber, and a piston in the chamber. 125

5. In a compression operated ignition device, the combination with an engine cylin- 130

der, of an igniter in the cylinder provided with a piston chamber, with means for affording the escape of gases from said piston chamber to the atmosphere, and a piston 5 in the chamber.

6. In a compression operated ignition device, the combination with an engine cylinder, of an igniter in the cylinder provided with a piston chamber, a hollow piston in 10 the chamber, and means for admitting atmospheric air to the interior of the piston and for permitting the escape of said air therefrom.

7. In a compression operated ignition device, the combination with the igniter provided with a piston chamber, of a piston in the chamber, a casing mounted on the igniter, electrodes in the igniter, a generator in the casing, an armature shaft in the 20 generator, operative connections between the shaft and piston, and a spring exterior of the casing for actuating the shaft, and an electric circuit between the electrodes including the spring in said circuit.

8. In a compression operated ignition device, the combination with the igniter, of a casing, an armature shaft in the generator, an arm on the casing adjacent the shaft, a crank on the shaft, a spring connecting the 30 crank and arm, an armature winding on the shaft, a terminal on the winding grounded in the shaft, a circuit wire from the winding extending to the crank, and a circuit wire extending from the expansion spring to one 35 of the electrodes.

9. In a compression operated ignition device, the combination with the igniter and casing, of a piston in the igniter actuated by the engine charge, an oscillatory armature shaft mounted in the casing, a piston 40 shaft in the casing operatively connected with the armature shaft, a head on the pis-

ton shaft, said casing being provided with an air chamber in the path of the head, a sleeve slidably mounted in the chamber, and a wall on the end of the sleeve in the path 45 of the head and provided with an opening adapted to be closed by the head.

10. In a compression operated ignition device, the combination with the igniter and casing, of a piston in the igniter actuated by the engine charge, an oscillatory armature shaft mounted in the casing, a piston shaft in the casing attached to the piston and operatively connected with the armature 50 shaft, a head on the piston shaft, said casing being provided with an air chamber in alignment with the piston shaft, a reciprocatory sleeve in the chamber surrounding the head, a wall on one end of the sleeve provided with an air opening in the path of the head, and a flange on the other end of the 55 sleeve also in the path of the head.

11. In a compression operated ignition device, the combination with the igniter and casing, of a piston in the igniter, an oscillatory armature shaft in the casing, a piston shaft on the piston extending into the casing 60 engaging the armature shaft, a head on the piston shaft, said casing being provided with an air chamber in alignment with the piston, a seat in the casing at one end of the air chamber, a sleeve slidably mounted in the chamber and surrounding the head, a wall 65 on the end of the sleeve provided with an opening in the path of the head, and a spring in the seat extending into the chamber.

In testimony whereof I have affixed my signature in presence of two witnesses.

WARREN F. STANTON.
